SEE-THRU LOUNGE BOARD

Edward A. Nicholson, Islip, N.Y., assignor to Surf-Jet
Manufacturing, Inc., Deer Park, N.Y.

Filed Feb. 5, 1970, Ser. No. 21,289

Term of patent 14 years

Int. Cl. D21—03

U.S. Cl. D71—1

FIG. 4

FIG. 5

FIG. 1 is a top plan view of the see-thru lounge board of the invention;

FIG. 2 is a side-elevational view thereof, the opposite side not shown being identical to the side shown;

FIG. 3 is a front end view thereof;

FIG. 4 is a bottom plan view of the see-thru lounge board;

FIG. 5 is a rear end view thereof; and

FIG. 6 is a cross-sectional view taken along the lines 6—6 of FIG. 1.

I claim:

The ornamental design for a see-thru lounge board, substantially as shown and described.
